Specification for Design.

Patented May 18, 1920.

Application filed January 27, 1919. Serial No. 273,496. Term of patent 14 years.

To all whom it may concern:

Be it known that I, CHARLES A. MASSING, a citizen of the United States, residing in Millcreek township, in the county of Erie and State of Pennsylvania, have invented a new, original, and ornamental Design for a Cooking-Receptacle, of which the following is a description, reference being had to the accompanying drawing, forming a part thereof wherein—

The drawing is a plan view of a cooking receptacle showing my new design. It is

formed of a cluster of radially - arranged heart-shaped receptacles with the points extending toward the center and the edges joined forming a star-shaped receptacle at the center of the cluster.

What I claim as new is:

The ornamental design for a cooking receptacle as shown.

CHARLES A. MASSING.
